US00D852190S

(12) **United States Design Patent** (10) **Patent No.:** **US D852,190 S**
(45) **Date of Patent:** ** *Jun. 25, 2019

(54) **TRANSCEIVER**

(71) Applicant: **Senseonics, Incorporated**,
Germantown, MD (US)

(72) Inventor: **Casey Haigh**, Germantown, MD (US)

(73) Assignee: **Senseonics, Incorporated**,
Germantown, MD (US)

(*) Notice: This patent is subject to a terminal disclaimer.

(**) Term: **15 Years**

(21) Appl. No.: **35/503,754**

(22) Filed: **Apr. 4, 2017**

(80) **Hague Agreement Data**

Int. Filing Date: **Apr. 4, 2017**

Int. Reg. No.: **DM/096878**

Int. Reg. Date: **Apr. 4, 2017**

Int. Reg. Pub. Date: **Oct. 6, 2017**

Related U.S. Application Data

(63) Continuation of application No. 29/579,877, filed on Oct. 4, 2016, now Pat. No. Des. 814,463.

(57) **CLAIM**

The ornamental design for a transceiver, as shown and described.

DESCRIPTION

Fig. 1.1 is a perspective view of the bottom, rear, and right side of the transceiver;

Fig. 1.2 is a perspective view of the top, front, and left side of the transceiver;

Fig. 1.3 is a rear view of the transceiver;

Fig. 1.4 is a front view of the transceiver;

Fig. 1.5 is a left side view of the transceiver;

Fig. 1.6 is a right side view of the transceiver;

Fig. 1.7 is a top view of the transceiver; and

(Continued)

Fig. 1.8 is a bottom view of the transceiver.
The portions of the transceiver shown in broken lines form
no part of the claimed design.

1 Claim, 8 Drawing Sheets
